(57) **ABSTRACT**

A new and distinct cultivar of *Chrysanthemum* plant named 'Yoelena', characterized by its upright, outwardly spreading and mounding plant habit; freely branching habit; dense and full plant habit; uniform and freely flowering habit; decorative-type inflorescences with dark yellow-colored ray florets; and natural season flowering about September 17th in the Northern Hemisphere.

1 Drawing Sheet

1

Botanical designation: *Chrysanthemum×morifolium*.
Cultivar denomination: 'YOELENA'.

BACKGROUND OF THE INVENTION

The present invention relates to a new and distinct cultivar of *Chrysanthemum* plant, botanically known as *Chrysanthemum×morifolium*, commercially grown as a perennial garden *Chrysanthemum*, and hereinafter referred to by the name 'Yoelena'.

The objective of the breeding program is to create new perennial garden-type *Chrysanthemum* cultivars having uniformly rounded plant habit, inflorescences with desirable inflorescence forms, attractive floret colors and good garden performance.

The new *Chrysanthemum* originated from a cross-pollination made by the Inventor in December, 2003, in Salinas, Calif. of *Chrysanthemum×morifolium* 'Gold Crest', disclosed in U.S. Plant Pat. No. 11,606, as the female, or seed, parent with *Chrysanthemum×morifolium* 'Red-bronze Urano', not patented, as the male, or pollen, parent. The new *Chrysanthemum* was discovered and selected by the Inventor as a single flowering plant within the progeny of the stated cross-pollination in a controlled greenhouse environment in Alva, Fla. in October, 2004.

Asexual reproduction of the new *Chrysanthemum* by vegetative cuttings was first conducted in a controlled greenhouse environment in Alva, Fla. in December, 2004. Asexual reproduction by cuttings has shown that the unique features of this new *Chrysanthemum* are stable and reproduced true to type in successive generations.

SUMMARY OF THE INVENTION

Plants of the new *Chrysanthemum* have not been observed under all possible environmental conditions. The phenotype may vary somewhat with variations in environment such as temperature, daylength and light intensity, without, however, any variance in genotype.

2

The following traits have been repeatedly observed and are determined to be the unique characteristics of 'Yoelena'. These characteristics in combination distinguish 'Yoelena' as a new and distinct garden *Chrysanthemum* cultivar:

- 5 1. Upright, outwardly spreading and mounded plant habit.
2. Freely branching habit; dense and full plant habit.
3. Uniform and freely flowering habit.
4. Decorative-type inflorescences.

- 10 5. Dark yellow-colored ray florets.
6. Natural season flowering occurs about September 17th in the Northern Hemisphere.

In side-by-side comparisons conducted in Alva, Fla., plants of the new *Chrysanthemum* differed from plants of the 15 female parent, 'Gold Crest', in the following characteristics:

1. Plants of the new *Chrysanthemum* were more rounded than plants of 'Gold Crest'.
2. Plants of the new *Chrysanthemum* were stronger than plants of 'Gold Crest'.
3. Plants of the new *Chrysanthemum* flowered five days earlier than plants of 'Gold Crest' when grown under natural season conditions.
4. Plants of the new *Chrysanthemum* had slightly smaller inflorescences than plants of 'Gold Crest'.

In side-by-side comparisons conducted in Alva, Fla., plants of the new *Chrysanthemum* differed from plants of the male parent, 'Red-bronze Urano', in the following characteristics:

- 30 1. Plants of the new *Chrysanthemum* were larger than plants of 'Red-bronze Urano'.
2. Plants of the new *Chrysanthemum* had larger inflorescences than plants of 'Red-bronze Urano'.
3. Plants of the new *Chrysanthemum* and 'Red-bronze Urano' differed in ray floret color as plants of 'Red-bronze Urano' had faded red-bronze-colored ray florets.

Plants of the new *Chrysanthemum* can be compared to plants of *Chrysanthemum×morifolium* 'Jessica', disclosed in

U.S. Plant Pat. No. 7,587. In side-by-side comparisons conducted in Alva, Fla., plants of the new *Chrysanthemum* differed from plants of 'Jessica' in the following characteristics:

1. Plants of the new *Chrysanthemum* were more compact and more rounded than plants of 'Jessica'.
2. Foliage of plants of the new *Chrysanthemum* maintain green color whereas foliage of plants of 'Jessica' do not maintain green color throughout the growing season.

Plants of the new *Chrysanthemum* can be compared to plants of *Chrysanthemum × morifolium* 'Gedi One Ces', disclosed in U.S. Plant Pat. No. 13,797. In side-by-side comparisons conducted in Alva, Fla., plants of the new *Chrysanthemum* differed from plants of 'Gedi One Ces' in the following characteristics:

1. Plants of the new *Chrysanthemum* had smaller inflorescences than plants of 'Gedi One Ces'.
2. Plants of the new *Chrysanthemum* flowered two to three weeks earlier than plants of 'Gedi One Ces' when grown under natural season conditions.

BRIEF DESCRIPTION OF THE PHOTOGRAPHS

The accompanying photographs illustrate the overall appearance of the new *Chrysanthemum*. These photographs show the colors as true as it is reasonably possible to obtain in colored reproductions of this type. Colors in the photographs may differ slightly from the color values cited in the detailed botanical description which accurately describe the colors of the new *Chrysanthemum*.

The photograph at the bottom of the sheet comprises a side perspective view of a typical flowering plant of 'Yoelena' grown in a container.

The photograph at the top of the sheet is a close-up view of typical inflorescences of 'Yoelena'.

DETAILED BOTANICAL DESCRIPTION

The aforementioned photographs and following observations and measurements describe plants grown in Alva, Fla., during the late spring and summer in a polycarbonate-covered greenhouse and under conditions and practices which approximate those generally used in commercial garden *Chrysanthemum* production. During the production of the plants, day temperatures averaged 32° C. and night temperatures averaged 21° C. Plants were grown in 15-containers under short day/long night conditions. Plants were ten weeks from planting when the photographs and description were taken. In the following description, color references are made to The Royal Horticultural Society Colour Chart, 1995 Edition, except where general terms of ordinary dictionary significance are used.

Botanical classification: *Chrysanthemum × morifolium* 'Yoelena'.

Parentage:

Female, or seed, parent.—*Chrysanthemum × morifolium* 'Gold Crest', disclosed in U.S. Plant Pat. No. 11,606.

Male, or pollen, parent.—*Chrysanthemum × morifolium* 'Red-bronze Urano', not patented.

Propagation:

Type.—Terminal vegetative cuttings.

Time to initiate roots.—About four days at temperatures of about 21° C.

Time to produce a rooted young plant.—About ten to twelve days at temperatures of about 21° C.

Root description.—Fine, fibrous; white in color.

Rooting habit.—Freely branching.

Plant description:

Appearance.—Perennial decorative-type garden *Chrysanthemum*. Stems upright and outwardly spreading giving a uniformly mounded appearance to the plant. Freely branching habit, about six lateral branches each with multiple secondary branches; pinching is not required; dense and full plant habit. Strong and vigorous growth habit.

Plant height.—About 18.5 cm.

Plant width.—About 36 cm.

Lateral branches.—Length: About 16 cm. Diameter: About 4 mm. Internode length: About 1.3 cm. Strength: Strong. Texture: Pubescent; longitudinally ridged. Color: Close to 148B.

Leaves.—Arrangement: Alternate, simple. Length: About 6 cm. Width: About 4 cm. Apex: Broadly acute. Base: Attenuate. Margin: Palmately lobed, sinuses between lateral lobes mostly parallel. Texture, upper and lower surfaces: Pubescence; veins prominent on lower surface. Color: Developing foliage, upper surface: Close to 147A. Developing foliage, lower surface: Close to 137A. Fully expanded foliage, upper surface: Close to 147A; venation, close to 147B. Fully expanded foliage, lower surface: Close to 147B; venation, close to 147B. Petiole: Length: About 3.5 cm. Diameter: About 2 mm. Texture, upper and lower surfaces: Pubescent. Color, upper and lower surfaces: Close to 148B.

Inflorescence description:

Appearance.—Decorative-type inflorescence form with narrowly oblanceolate-shaped ray florets. Inflorescences borne on terminals above foliage. Disc and ray florets arranged acropetally on a capitulum. Inflorescences fragrant, pungent.

Flowering response.—Under natural season conditions, plants flower about September 17th in the Northern Hemisphere.

Postproduction longevity.—Inflorescences maintain good color and substance for about four weeks in an outdoor nursery. Inflorescences persistent.

Quantity of inflorescences.—About 14 to 17 inflorescences develop per lateral branch.

Inflorescence bud.—Height: About 1.5 cm. Diameter: About 1.1 cm. Shape: Oblate. Color: Close to 12B.

Inflorescence size.—Diameter: About 5.8 cm. Depth (height): About 2.3 cm. Disc diameter: About 2 mm. Receptacle diameter: About 1.7 cm. Receptacle height: About 6 mm. Receptacle color: Close to 147A.

Ray florets.—Shape: Narrowly oblanceolate. Orientation: Initially upright, then about 90° from vertical. Aspect: Initially incurved, then mostly flat; apices reflex with development. Length: About 3 cm. Width: About 8 mm. Apex: Emarginate to erose. Base: Acute. Margin: Entire. Texture, upper and lower surfaces: Smooth, glabrous; velvety; longitudinally ribbed. Number of ray florets per inflorescence: About 175 arranged in about ten whorls. Color: When opening and fully opened, upper surface: Close to 13B; color does not fade with development. When opening and fully opened, lower surface: Close to 13C; color does not fade with development.

Disc florets.—Shape: Tubular, elongated. Length: About 2 mm. Diameter: Less than 1 mm. Number of

disc florets per inflorescence: About five to ten. Color, immature and mature: Apex: Close to 154A. Mid-section: Close to 154C. Base: Close to 145C.

Phyllaries.—Number of phyllaries per inflorescence: About 24 arranged in about three whorls. Length: About 8 mm. Width: About 2 mm. Shape: Lanceolate. Apex: Acute. Base: Truncate. Texture, upper surface: Smooth, glabrous. Texture, lower surface: Pubescent. Color, upper surface: Close to 148B to 148C. Color, lower surface: Close to 148A.

Peduncles.—Length, terminal peduncle: About 5.2 cm. Length, fourth peduncle: About 7 cm. Diameter, terminal peduncle: About 1.5 mm. Angle: Mostly upright to 45° from vertical. Strength: Strong. Texture: Pubescent. Color: Close to 147B.

Reproductive organs.—Androecium: Not observed. Gynoecium: Pistil length: About 5 mm. Stigma shape: Bi-parted. Stigma color: Close to 5A. Style

length: About 3 mm. Style color: Close to 1B. Ovary color: Close to 155A.

Seed/fruit.—Seed and fruit production has not been observed.

Disease/pest resistance: Resistance to pathogens and pests common to *Chrysanthemums* has not been observed on plants grown under commercial conditions.

Garden performance: Plants of the new *Chrysanthemum* have demonstrated excellent garden performance and will overwinter in USDA Zones 5 and higher; plants of the new *Chrysanthemum* have been observed to tolerate high temperature of about 38° C.

It is claimed:

1. A new and distinct *Chrysanthemum* plant named 'Yoel-ena' as illustrated and described.
